UNITED STATES PATENT OFFICE.

ELMER FORREST ESTES, OF LINCOLN, NEBRASKA.

METHOD AND APPARATUS FOR SINKING PILING.

1,347,688.

Specification of Letters Patent.

Patented July 27, 1920.

Application filed July 3, 1918. Serial No. 243,188.

To all whom it may concern:

Be it known that I, ELMER F. ESTES, a citizen of the United States, and a resident of Lincoln, in the county of Lancaster and 5 State of Nebraska, have invented certain new and useful Improvements in Methods and Apparatus for Sinking Piling, of which the following is a specification.

My present invention relates generally to 10 a new method and apparatus for use in the hydraulic sinking of piling, and in the course of which operation there is to be overcome a side pressure of the surrounding earth against the sides of the piling, that may be 15 likened in part to that occurring in the excavation of a well when a cave-in is threatened.

In general, piling is hydraulically sunk 20 by forcing water downwardly into the ground so as to soften the same to the consistency of mud in order to permit the piling to lower into place. As the piling lowers it is evident that there will be an increasingly active friction developed between 25 the same and the side walls of the opening it has made, and to avoid this disadvantage many devices have been employed to produce a film of water between the piling and the surrounding earth. So far as I am 30 aware, however, all such devices and methods have contemplated and practised the emission of the water away from the piling and have been found ineffective for this reason as well as lack of mobility.

35 In the first instance the water emitted away from the piling is taken up at once by the surrounding earth instead of forming a lubricating film between the earth and the piling, and in the second instance the devices lack desired adjustability so that they 40 may be moved with respect to the surface of the piling and adjusted from point to point dependent upon where their greatest need is felt.

45 My present method contemplates the use of a water emitting arrangement capable of movement along the piling and of the emission of a sheet of water against the piling so that it will in this manner be calculated 50 to bring about the desired lubrication between the piling and the adjacent earth.

As to the apparatus my invention contemplates a movable device in the nature of a 55 scraper having a water discharge aperture of slot-like formation, although the invention is capable of more simple construction

in carrying out the method described above and as will be hereinafter more fully set forth.

In the accompanying drawings which 60 illustrate various devices embodying the invention,

Figure 1 is a vertical section illustrating piling in the course of setting,

Fig. 2 is a detail perspective view of a 65 form of water emitting scraper embodying the invention,

Figs. 3 to 9 inclusive are vertical sectional views through modified forms of scrapers,

Fig. 10 is an elevation of a more simple 70 form of water emitting device, and

Figs. 11 and 12 are respectively a vertical and horizontal section through the device of Fig. 10.

Referring now to these figures, the 75 method of my present invention consists in the utilization of a movable water emitting apparatus capable of adjustment on the piling or continuously shiftable with respect thereto, and the discharge of water from 80 such device toward and against the surface of the piling on which the device is movable whereby the water will be caused to impinge upon the piling and in this way assure delivery between the piling and the earth in 85 such manner that a minimum portion of the water so delivered will be absorbed by the earth and a maximum portion thereof will remain to furnish the desired lubrication for the piling in its movement downwardly 90 through the earth.

As to apparatus, my invention is capable of being carried out with a variety of devices each of which is however mounted at the end of a water delivery pipe which is 95 lowered alongside of the piling, and may be of the simple form shown in Figs. 10, 11, and 12 where the delivery pipe 15 is connected at its extremity, by means of T-coupling 16, to lateral pipes 17 closed at 100 their outer ends by caps 18, the pipes 17 as well as the T-coupling 16, having lengthwise slots in alignment with one another to form a water emission slot approximating the width of the adjacent face of the piling. 105 The slots of these figures appear at 19.

In the form of the invention shown in Figs. 1 and 2, in the former of which several hollow scraper like bodies 20 may be seen along different faces of the piling, the 110 outer surface of the delivery member is convex as at 21, and a portion at least of its

inner surface concave as seen at 22, its inner face having a water emitting slot 23 approximating the width of the adjacent face of the piling as will be seen by reference to Fig. 1. This slot 23 communicates with the hollow body of the member 20 and the latter has an extending nipple 25 which provides for its convenient attachment to the respective water delivery pipe 26 of Fig. 1.

As seen in Fig. 3 the water emitting member 27 is convex on the outside as at 28 and has a concave inner face 29 provided at an intermediate point with a water emitting slot 30 differing from the form shown in Fig. 4 where the member 31 is generally of the shape of Figs. 1 to 3 inclusive. The water emitting member may have water emission slots 32 both above and below its inner concave face 33. As seen in Fig. 5 the discharge slot or orifice 34 may be located in an upper extension 35 leaving the lower edge 36 entirely free to function as a scraper, and in accordance with the form shown in Fig. 6 the scraper like discharge member 37 may have a flat inner face 38, doing away with the concave and with the emission slot 39 adjacent its lower scraping edge.

According to the form of Fig. 7 the body of the scraping member 40 may be elongated so that by the interposition of an intermediate grooved portion 41 two scraping edges 42 and 43 may result as well as two discharge heads, each having water emission slots 34.

According to the form shown in Fig. 8 the body of the water discharge member 45 may approach the crescent shape as shown so as to increase the effectiveness of its scraping edges 46, and the water emission slot 47 may be either single as seen in Fig. 8 or double as seen at 48 in connection with the member 49 of Fig. 9.

It will be observed however that in every instance the description relates to an apparatus movable along the exterior of the piling and capable of delivering, emitting or discharging a thin uniform stream or sheet of water toward the piling in order to cause the same to impinge against the piling and thus bring about its disposition between the piling and the earth through which it is desired to lubricate the movement of the piling.

It is obvious therefore that each of the modified forms of apparatus is well calculated to carry out the method involved and

that to this extent at least the means employed may be changed or varied at will. 60

I claim:

1. The improved method of aiding the sinking of piling which consists in scraping the sides of the piling and discharging water directly against the surface of the piling from points beyond the sides of the piling as described. 65

2. The improved method of aiding the sinking of piling which consists in continuously scraping the sides of the piling as it lowers into the ground and at the same time delivering water in streams directly toward and impinging upon the surface of the piling as described. 70

3. The improved method of aiding the sinking of piling which consists in the utilization of pile scraping devices shiftable along the sides of the piling adjacent the surface thereof during the pile sinking operation, and the discharge of water from such devices directly against the said adjacent surface of the piling as described. 75

4. The improved method of aiding the sinking of piling which consists in the utilization of pile scraping and water emission devices shiftable along the sides of the piling adjacent the surface thereof and during the sinking operation, and a discharge of water in sheets against the said adjacent surface of the piling as described. 80 85

5. An apparatus of the character described, for use in connection with piling, consisting of a discharge head movable independently of the piling alongside thereof during the sinking of the piling and having a scraper and a discharge slot opening toward the piling for delivering a sheet of water against the latter. 90

6. An apparatus of the character described, consisting of a scraper shiftable along the surface of the piling during the sinking of the piling, having a discharge orifice at one side opening toward the piling for the purpose described. 100

7. A device of the character described, comprising a hollow member having scraping edges for engagement with the surface of piling, said member being movable along the piling during the sinking operation and having a discharge slot opening toward an object engaged by the said scraping edges. 105 110
